ABSTRACT OF THE DISCLOSURE

A process for preparing overbased barium olefin sulfonates featuring the use of (1) barium sulfide treated with acetic acid, (2) olefin sulfonic acids, and (3) sulfur dioxide; a product obtained from this process and the use of these products in distillate fuels are described.

BACKGROUND OF THE INVENTION

This invention is directed to a method of preparing overbased barium sulfonates and their use in distillate fuels.

Processes for preparing overbased alkaline earth oil soluble sulfonates are available in the art (see e.g. U.S. 2,617,049, U.S. 2,956,018, U.S. 3,027,325, and U.S. 3,312,618). The principal products disclosed in the art appear to be those prepared from petroleum derived sulfonic acids. These petroleum derived sulfonic acids are in general alkaryl sulfonates obtained as side products from the sulfuric acid treatment of petroleum hydrocarbons in refining operations.

The term overbased indicates that the resultant product from these various processes contains an amount of alkaline earth metal greater than the stoichiometric amount of metal which would be present if the particular sulfonic acid were fully neutralized. The theory of this overbased complex formation is not fully understood. One suggestion has been that the oil soluble sulfonates act as protective colloids or dispersants thus keeping an alkaline earth compound suspended in a fluid carrier.

A general method of preparing these complexes features the *in situ* formation of a finely divided alkaline earth compound such as CaCO_3 or CaSO_3 , in the presence of a petroleum sulfonate in a hydrocarbon medium. This is accomplished by introducing an acidic gas such as carbon dioxide or sulfur dioxide into an alkaline earth containing, petroleum sulfonate dispersion in a hydrocarbon medium. Recent improvements in this process feature the use of promoters such as low molecular weight alcohols, phenols, amines, and the like.

When barium sulfide is utilized as a barium source, attempting to overbase by introducing sulfur dioxide gas into the reaction mixture presents a problem. The problem is that during the course of this reaction free sulfur is formed. This sulfur is an undesirable contaminant in the overbased barium sulfonate product.

It has been discovered that the formation of sulfur during the overbiasing step using SO_2 can be effectively eliminated by treating the barium sulfide with acetic acid prior to carrying out the overbasing reaction. In addition, the treatment with acetic acid increases the utilization of barium when a crude barium sulfide such as "black ash" is used as a barium source. The overbased barium sulfonates prepared in this manner are useful as distillate fuel smoke suppressors; and these products additionally exhibit good resistance to emulsification.

The present invention provides a method of preparing overbased barium olefin sulfonates featuring the use of barium sulfide treated with acetic acid as the barium

source and SO_2 as the acidic gas. The products are effective smoke suppressors in diesel fuels.

SUMMARY OF THE INVENTION

- 5 A process for preparing overbased barium sulfonates from an olefin sulfonic acid, barium sulfide, acetic acid and sulfur dioxide in the presence of C_1-C_5 alkanol and water in a hydrogen medium; the product obtained by this process and its use as a smoke reducing distillate fuel additive.

DESCRIPTION OF THE PREFERRED EMBODIMENTS

- 15 A preferred embodiment of this invention is a process for preparing an overbased barium sulfonate which comprises

- 20 (1) preparing a mixture of barium sulfide in from about 100 to about 800 parts by weight of C₁-C₅ alkanol per mole of barium sulfide, adding at least an equimolar amount of water based on barium sulfide and at least 2 moles of acetic acid per mole of barium sulfide,

25 (2) heating said mixture to reflux and maintaining said temperature until the evolution of H₂S has substantially stopped,

30 (3) adding thereto a mixture of an inert hydrocarbon medium and an olefin sulfonic acid, prepared by sulfonating a mixture of acyclic, monoolefins having from about 12 to about 32 carbon atoms, such that the molar ratio of barium sulfide to said sulfonic acid is from about 1:1 to about 10:1,

35 (4) introducing sulfur dioxide gas into the heated mixture of step (3) until the sulfur dioxide effluent rate is substantially equal to the sulfur dioxide impurity rate, and

(5) distilling substantially all the alkanol, acetic acid and water from said mixture.

40 Barium sulfide in the crude form known as "black ash" is a most preferred form of BaS.

Olefin sulfonic acids are used in the present process. These sulfonic acids are products obtained on sulfonating olefins. In sulfonating the olefin, any suitable sulfonation process may be utilized. Suitable procedures are described in the following patents: U.S. 3,259,645; U.S. 3,337,437; British 1,072,601; French 1,403,407; and French 1,399,570. Olefin sulfonic acids prepared by treating olefins with SO_3 are especially useful sulfonic acids.

50 The olefin sulfonic acids are generally mixtures containing alkenyl sulfonic acids, hydroxyalkyl (or -alkenyl) sulfonic acids, disulfonic acids, and 5 and 6 members cyclic inner esters called sultones. The alkenyl and hydroxyalkenyl (or alkenyl) sulfonic acids generally predominate in these mixtures. The general nature of olefin sulfonation processes, mechanisms and product compositions obtained are described in the journal entitled "Hydrocarbon Processing," vol. 47, No. 3, pages 109-114, March 1968; and the material therein described is incorporated by reference.

Olefins which are used for preparing the olefin sulfonic acids are acyclic monoolefins having from about 12 to about 32 carbon atoms and preferably from about 14 to about 32 carbon atoms. By olefins, I mean olefin hydrocarbons. Olefins which are especially useful for sulfonation are synthesized by methods known in the art; for example, they may be prepared by cracking wax paraffins by dehydrogenating paraffin hydrocarbons or by polymerizing low molecular weight olefins such as ethylene or propylene, using Ziegler type catalysts. It is the general nature of these olefin preparations that mixtures of olefins are obtained. These olefin mixtures can vary widely in

composition from 100% alpha monoolefin through intermediate mixtures, to 100% internal monoolefins. The range of carbon chain lengths in these mixtures can also vary considerably. Both branched and linear olefins can be present in these mixtures. Useful mixtures can also contain small amounts of olefins outside the C₁₂–C₃₂ range. Mixtures in which alpha monoolefins predominate are preferred. By predominate is meant that more than 50% by weight of the olefin mixture is alpha monoolefin.

Examples of useful olefin mixtures are those having the following olefin composition by weight: 30% C₁₂, 40% C₁₄, and 30% C₁₆; 10% C₁₃, 20% C₁₄, 25% C₁₅, C₁₆, 15% C₁₇, and 5% C₁₈; 2% C₈, 3% C₁₀, 5% C₁₂, 30% C₁₄, 40% C₁₆, 50% C₁₈, and 5% C₂₀; 1% C₆, 1% C₈, 2% C₁₀, 15% C₁₂, 21% C₁₄, 24% C₁₆, 20% C₁₈, 10% C₂₀, 4% C₂₂, and 2% C₂₄; 50% C₁₄, and 50% C₁₆, 5% C₂₃, 15% C₂₄, 30% C₂₅, 32% C₂₆, 10% C₂₇, and 8% C₂₈; 15% C₂₉, 18% C₃₀, 30% C₃₁, 20% C₃₂, and 7% C₃₃; 6% C₂₆, 15% C₂₈, 40% C₃₀, 36% C₃₂, and 3% C₃₄.

Preferred mixtures of olefins are those containing even carbon number olefins ranging from about C₁₂ to about C₃₂; the olefins are predominately alpha monoolefins. These preferred olefins will be referred to as C₁₂–+ olefins. These preferred mixtures can also contain small amounts of C₁₀ and lower olefins as well as C₃₄ and higher olefins. These olefin mixtures can also contain paraffins as well as other by-products of the olefin preparation such as high molecular weight alcohols. Compositions of typical preferred olefin mixtures of this type are listed in the following table:

^a C₂₂ and higher olefins.

^b Includes all three olefin configurations.

A general composition range of these C₁₄–+ olefins comprises a mixture containing 0–3% C₁₂, 8–35% C₁₄, 15–30% C₁₆, 8–25% C₁₈, 4–15% C₂₀, 4–15% C₂₂, 4–15% C₂₄, 0–10% C₂₆, 0–10% C₂₈, 0–5% C₃₀, 0–5% C₃₂+, containing 60–80% olefins, 20–35% paraffins and 1–5% alcohols.

Another preferred olefin mixture useful for sulfonation is a mixture of predominately alpha monoolefins of even carbon number ranging from C₁₈–C₂₈. Again, small amounts of olefins outside this carbon number range can also be present; some paraffins and other by-products, e.g. alcohols, can also be present. These preferred olefin mixtures will be referred to herein as C₁₈–+ olefins. A general composition range of these C₁₈–+ olefins is set out in the following table.

Barium sulfide is the reactant utilized in the present process to supply the barium values for the overbased product. A preferred form of barium sulfide is a crude product obtained in the commercial preparation of barium sulfide by reducing a barium sulfate ore with carbon. This crude product is commonly called black ash; it ordinarily contains up to about 90 percent barium sulfide.

Typical analysis of commercial black ash is as follows; all percentages are by weight.

Black ash typical analysis

	Percent
Assay BaS	71.2-88.0
Insoluble material	19.2-10.4
Calcium and strontium (as oxides)	0.5
Silica	0.4
Aluminum and iron (as oxides)	1.5
Carbon	3.7
Magnesium (as oxide)	0.2
Thio and other reducible sulfur compounds	2.8

The ratio of the reactants used in the present process may be varied. It is essential, however, that a greater than stoichiometric amount, based on the olefin sulfonic acid value, of the inorganic barium compound be used in the process. The acid value of the olefin sulfonic acid is obtained by determining either the saponification number of acid number of the sulfonic acid. The saponification number is the number of milligrams of potassium hydroxide required to saponify one gram of olefin derivative; the acid number is the number of milligrams of KOH required to neutralize one gram of the sulfonated olefin derivative. The saponification number in the case of the olefin sulfonic acid containing only free sulfonic acids is equivalent to the acid number; and thus either determination will account for all sulfonic acid values. The saponification number rather than the acid number is preferably used for the olefin sulfonic acids which contain mixtures of sulfonic acids and the inner ester sulfones. From this saponification (or acid) number, the combining value or acid value of the olefin sulfonic acid is calculated.

The stoichiometric amount of barium sulfide is that amount required to fully neutralize the olefin sulfonic acid. Since the present process produces an overbased product, that is, one in which more than the stoichiometric amount of barium is present, the amount of barium sulfide used must be greater than the stoichiometric amount indicated above. In general, from 2 to 20 times the stoichiometric amount of the barium sulfide is used in the present invention; an amount of from 4 to 10 times the stoichiometric amount is preferred. Expressed in moles of olefin sulfonic acid to barium sulfide, ratios of 1:1 up to 1:10 are useful; sulfonic acid to BaS ratios of 1:2 to 1:5 are preferred, and 1:3 to 1:4 are most preferred.

The reaction of the present process can be carried out in a suitable hydrocarbon medium. The medium is characterized by being (1) inert during the process of the reaction and (2) a solvent for the sulfonic acid starting material. It is also preferred that this medium be a solvent for the overbased product which is obtained in the process; and this hydrocarbon medium should be compatible with distillate fuel oil, and especially diesel fuel. Any hydrocarbon which meets these criteria may be used. Aromatic hydrocarbons, paraffinic hydrocarbons, olefinic hydrocarbons, mixtures thereof, light distillate hydrocarbon oils, distillate fuels, kerosene, straight run naphtha, petroleum refinery streams such as catalytic reformate, thermally or catalytically cracked streams, alkylated refinery streams, catalytically cracked naphtha and the like, are useful hydrocarbon media. Benzene, C_1-C_6 alkylbenzenes such as toluene, xylene, acetylbenzene, pentylbenzene and the like, C_6-C_{12} paraffins such as hexane, heptane, decane and the like, aviation alkylate, light processing oils such as No. 9 oil, pale oil and the like, catalytic

reformate containing over about 70 percent aromatic hydrocarbons and the like, and mixtures thereof are some examples of useful media.

The amount of hydrocarbon medium used in the process is not critical. An amount of inert hydrocarbon ranging from about 0.5 to about 10 times the weight of the olefin sulfonic acid can be used.

Alkanols having from about 1 to about 5 carbon atoms are used in the present process. The exact function of the alkanol used in the process is not understood; however, the alkanol is required in order for the reaction of the present process to be carried out. Examples of useful alkanols are ethanol, isopropanol, pentanol-3, amyl alcohol, butyl alcohol, and mixtures of these alcohols. Methanol is a most preferred alkanol.

The amount of alkanol used may be varied. Generally the barium sulfide reactant is dispersed in the alkanol as an initial step. The amount of alkanol used is based on the amount of barium sulfide used. Thus, amounts of alkanol ranging from about 100 to about 800 parts by weight per mole (167 parts by weight) of barium sulfide are generally used.

Water is also required in the present process. Ordinarily an equimolar amount of water based on amount of barium sulfide is used. A larger amount of water, for example up to 2 times the necessary amount, can also be used. The water, excess acetic acid (and alkanol) has to be distilled off as a final step in the process. As a practical matter then, too large an excess of water is not used. Acetic acid is a critical component of the present invention. At least two moles of acetic acid per mole of barium sulfide reactant are required in the present process. Generally, up to three moles of acetic acid per mole of barium sulfide can be used. Amounts in excess of this are ordinarily not required. After the barium sulfide, alkanol, water and acetic acid are blended, the mixture is heated generally to the reflux temperature and held there until evolution of H_2S is substantially complete.

The process is carried out at elevated temperatures. Reaction temperatures of about 50° C. and higher are ordinarily used. The reaction can conveniently be carried out at the reflux temperature. The reflux temperature, of course, will be dependent upon the particular hydrocarbon medium used, its amount, and the amount of alkanol and water in the reaction mixture. An upper temperature limit would be about 150° C. although higher reaction temperatures may be used. This reaction temperature is the temperature at which the sulfur dioxide is passed into the reaction mixture to effect formation of the overbased complex.

The mixture containing the olefin sulfonic acid material in hydrocarbon medium, barium sulfide, acetic acid, water and alkanol is subjected to treatment with sulfur dioxide gas; this is the overbasing step. The SO_2 is simply bubbled through the mixture at the aforesaid reaction temperatures until the SO_2 input rate is substantially equal to the rate at which the SO_2 is coming out of the mixture. At this point the overbasing reaction may be considered complete; ordinarily the overbasing reaction is completed within about an hour although longer reaction times, e.g. 3 hours, 8 hours, 24 hours, may be used. The input flow rate of the SO_2 will, of course, have an effect on the reaction rate and time. This treatment with SO_2 effectively complexes the stoichiometric excess of barium with the sulfonic acid, thus forming an overbased barium olefin sulfonate.

The flow of SO_2 need not be discontinued after the overbasing reaction is considered complete. Generally, the SO_2 flow is decreased at this time and maintained at this reduced rate while distilling off the water, alcohol and excess acetic acid.

The process of this invention is ordinarily carried out at atmospheric pressures. However, it can also be carried out above atmospheric. Pressures above atmospheric can

be used to advantage to minimize solvent loss while carrying out the reaction; higher pressures might also be desirable when a reaction temperature higher than the reflux temperature is used to carry out the reaction. The following examples illustrate the process of the present invention; all parts are by weight unless otherwise indicated. The pale oil used in each of the examples is a commercial product identified as Sun Circosol 410 and the naphtha used is an aviation alkylate.

EXAMPLE 1

A suitable vessel fitted with a dropping funnel, stirrer, thermometer, water collector and condenser was charged with 79.7 parts (0.4 mole) crude barium sulfide (85% assay) and 100 parts of methanol. About 14.5 parts of water (0.8 mole) was added with stirring, followed by the gradual addition over a 6-minute period of 54 parts (0.9 mole) of glacial acetic acid. This mixture was refluxed 5 hours (marked decrease in H_2S evolution was noted) and then cooled. To this mixture was added 44.5 parts (0.1 mole) of a C_{14+} olefin sulfonic acid (Saponification No.=126), 35 parts of pale oil and 180 parts of naphtha; the mixture was refluxed another 30 minutes. Sulfur dioxide was then bubbled into the mixture under reflux for 45 minutes at a rate of about 0.830 part/minute. The methanol was allowed to distill off and temperature was then raised to 147° C. to remove the water and acetic acid (about 140 parts of naphtha was added during this step as a processing aid). The mixture was then cooled and diluted with about 400 parts of benzene. The mixture was then filtered through a bed of Celite Filter-aid. The solvents were removed under vacuum. The overbased barium olefin sulfonate product obtained was a slightly hazy amber liquid. The yield was 166.4 parts. Analysis showed the product contained 30.8% barium (Ba) and 7.5% sulfur (S); infrared spectrum also showed some acetate present.

EXAMPLE 2

A suitable vessel fitted as in Example 1, was charged with 77 parts (0.4 mole) black ash (88% assay) and 100 parts methanol. About 14.4 parts of water were added with stirring followed by the gradual addition over an 8-minute period of 72 parts (1.2 moles) of glacial acetic acid. Nitrogen was then passed through the mixture while it was refluxed for 5.5 hours. The mixture was cooled. Then a solution of 44.5 parts (0.1 mole) of a C_{14+} olefin sulfonic acid (Saponification No.=126) and 180 parts naphtha was added and the mixture was refluxed for another 30 minutes. At this time, SO_2 was passed into the mixture for 75 minutes at the rate of about 0.830 part/minute. Next, the methanol was allowed to distill off and the temperature was raised to 145° C. to remove the remaining water and acetic acid. The mixture was cooled and it was then diluted with about 400 parts of benzene. This mixture was then filtered through a Celite Filter-aid bed. The solvents were removed from the filtrate under vacuum. A clear, amber, mobile, liquid product was obtained. Yield was 173.6 parts. Analysis showed 31.8% Ba and 7.4% S, infrared spectrum indicated presence of acetate.

EXAMPLE 3

The process of Example 2 was essentially repeated except that (1) 10 parts of water was used instead of 14.4 parts, (2) 45.5 parts (0.9 mole) of 91% formic acid was used in place of the acetic acid and (3) the first reflux period was 14.5 hours. When the SO_2 treatment was begun, there was immediate evidence of free sulfur forming in the mixture. The reaction was discontinued. This example is inserted to indicate the criticality of acetic acid in the present invention.

EXAMPLE 4

A vessel fitted as in Example 1 was charged with 77 parts (0.4 mole) black ash (88% assay) and 100 parts of methanol. While stirring about 14.4 parts of water was added followed by gradual addition of 60 parts (1.0 mole) of glacial acetic acid over a period of about 8 minutes. Nitrogen was then passed through this mixture while it was refluxed for about 5.5 hours. The mixture was then cooled. A solution of 44.5 parts (0.1 mole) as a C_{14+} olefin sulfonic acid (Saponification No.=126), 25 parts of pale oil and 180 parts of naphtha was added and the mixture was refluxed for 30 minutes. Then, SO_2 was passed into the mixture at a rate of about 0.830 part/minute for 75 minutes. The methanol was then distilled off. The mixture was then cooled to 85° C. and about 5 parts of water and about 140 parts of naphtha were added and, continuing the SO_2 flow into the mixture at about 0.184 part/minute, the mixture was again refluxed. Twice more while refluxing, 5 parts portions of water were added. Then the mixture was heated to 146.5° C. to remove the remaining water and acetic acid. The mixture was then cooled and diluted with benzene. This mixture was filtered through a Celite Filter-aid bed; and the solvents were removed under vacuum. The overbased product obtained was a clear, dark, mobile liquid. The yield was 181.6 parts. Analysis showed it to contain 30.9% Ba and 7.7% S; and the infrared spectrum indicated the presence of acetate.

In the Examples 1-4, the C_{14+} olefin sulfonic acid was a product prepared by SO_3 sulfonation of C_{14+} olefin composition F in Table 2.

EXAMPLE 5

A suitable vessel, fitted as in Example 1, was charged with 77 parts (0.4 mole) black ash (88% assay) and 100 parts methanol. About 14.4 parts (0.8 mole) of H_2O was added with stirring followed by the gradual addition over a 5-minute period, of 60 parts (1.0 mole) of glacial acetic acid. While passing nitrogen through, the mixture was refluxed for 6.5 hours. To this mixture was added 46.8 parts (0.086 mole) of C_{12+} olefin sulfonic acid (Saponification No.=103, 30 parts of pale oil and 180 parts of naphtha; the mixture was then refluxed for 30 minutes. Sulfur dioxide was then passed into the mixture for 68 minutes at about 0.830 part/minute. (It was noted that after 53 minutes the rate of SO_2 input and exhaust were about the same.) The SO_2 feed was then reduced to about 0.1 part/minute and the methanol, water and acetic acid were distilled off. The mixture was then cooled to 85° C., 5 parts of water and about 35 parts of naphtha were added and the mixture was refluxed; 11.8 parts of aqueous material were collected. The mixture was cooled again and 5 more parts of H_2O were added; 7.5 parts of an aqueous mixture were collected on refluxing. The mixture was cooled a third time and about 5 parts of water were added; about the same.) The SO_2 feed was then reduced to about fluxing. The mixture was then heated to 135° C. to remove the remaining water. On cooling, about 200 parts of benzene were added. This mixture was then filtered through a bed of Celite Filter-aid on a coarse frit. The solvents were removed under vacuum. The overbased barium sulfonate product obtained was a dark, clear fluid. Analysis showed 33.1% Ba and 8.1% S; infrared spectrum showed presence of some acetate.

EXAMPLE 6

The procedure of Example 5 was repeated except that no pale oil was added. The overbased barium sulfonate product obtained was extremely viscous; the yield was 133.05 parts. Analysis showed 40.1% Ba and 10.1% S. The infrared spectrum of this product showed some acetate present.

9

EXAMPLE 7

The procedure of Example 5 was repeated, but the following amounts of ingredients were used in place of those in Example 5.

96.25 parts (0.5 mole) black ash
18.0 parts (1 mole) water
72 parts (1.2 moles) glacial acetic acid

The product obtained was a moderately viscous liquid; the yield was 181.15 parts. Analysis showed 36.5% Ba and 9.0% S. Some acetate was present as shown by the product's infrared spectrum.

EXAMPLE 8

A vessel fitted with a dropping funnel, stirrer, thermometer and condenser was charged with 57.8 parts (0.3 mole) of black ash (88% assay) and 100 parts of methanol. About 10.8 parts (0.6 mole) of water were added with stirring followed by the gradual addition of 48 parts (0.8 mole) of glacial acetic acid over a 5-minute period. The mixture was then refluxed for about 7.5 hours. At the end of this time a solution of 42.8 parts of a C_{18+} olefin sulfonic acid (Saponification No.=110), 35 parts pale oil and 180 parts of naphtha was added and the mixture was refluxed for 30 minutes. Sulfur dioxide was then passed through the mixture at a rate of 0.830 part/minute for 51 minutes; and then the sulfur dioxide flow was reduced to 0.1 part/minute while the methanol, water and acetic acid were distilled off. The mixture was then cooled, about 5 parts of water were added, the mixture was brought to reflux and the aqueous layer that collected (in the water collector) was removed. This treatment (cooling, add 5 parts water, reflux and remove the aqueous layer) was repeated twice more. Then, the SO_2 flow was discontinued and the temperature was raised to 140° C. to remove the remaining water. On cooling, the product mixture was diluted with about 200 parts of benzene. This mixture was then filtered through a bed of Celite Filter-aid. Solvents were removed under vacuum. The resultant product obtained was a clear, dark mobile liquid; the yield was 146 parts. Analysis showed it to contain 27.7% Ba and 7.1% S. The infrared spectrum of the product showed the presence of some acetate.

The olefin sulfonic acid used in Example 8 was obtained by SO_3 sulfonating the following C_{18+} olefin composition; all percentages are by weight.

 C_{18+} olefin mixture

Carbon No.:

14	-----	Trace
16	-----	0.7
18	-----	9.5
20	-----	47.7
22	-----	26.8
24	-----	11.2
26	-----	3.5
28	-----	0.9
30	-----	0.2

Component type:

		Percent
α -	-----	
Vinyl olefin	-----	52.2
Vinylidene olefin	-----	11.6
Internal olefin	-----	32.9
Paraffins	-----	3.3
Alcohol	-----	—

EXAMPLE 9

A vessel fitted as in Example 8 was charged with 78.4 parts (0.4 mole) of black ash (86.5% assay) and 100 parts of methanol. About 14.4 parts (0.8 mole) of water was added with stirring followed by the rapid addition (1.5 minutes) of 60 parts (1.0 mole) of glacial acetic acid. The condenser was immediately connected to a gas scrubber containing 314.1 parts of 4 N sodium hydroxide. The reaction mixture was then brought to reflux and at

10

one-hour intervals about a 75 gram sample liquid was removed from the scrubber and then about 5 grams of water were added to the scrubber. Six samples were thus removed over a period of 7 hours.

At the end of this time, a solution of 46.8 parts (0.086 mole) of a C_{12+} olefin sulfonic acid (Saponification No.=103) in 60 parts of a C_{12+} olefin was added and about 16 parts of methanol were added. This mixture was refluxed for 30 minutes. Then SO_2 was passed through the mixture of 0.830 part/minute for 78 minutes. About 45 parts of methanol were distilled off at this time to reduce the viscosity of the mixture. The SO_2 rate was then reduced to 0.14 part/minute and the remaining alcohol, water, and acetic acid were distilled off. The temperature of the mixture was then raised to about 140° C. in order to remove the remaining water. The mixture was filtered through a Celite Filter-aid bed; and the solvents were removed under vacuum. The product obtained was a clear, dark liquid. The yield was 168.4 parts. Analysis showed 29.8% Ba and 8.03% S. The infrared spectrum showed the presence of acetate.

EXAMPLE 10

The procedure of Example 8 was repeated except that 30 parts pale oil were substituted for the 60 parts of C_{18+} olefin.

The product obtained was a moderately viscous fluid. The yield was 157.7 parts. Analysis showed 32.5% Ba and 8.26% S. The infrared spectrum showed some acetate present.

The olefin sulfonic acid used in Examples 5-7, 9 and 10 was obtained by SO_3 sulfonating the C_{12+} olefin composition D of Table 1.

EXAMPLE 11

A vessel fitted as in Example 1 was charged with 56.4 parts (about 0.3 mole) of black ash (89.6% assay) and 100 parts of methanol. To this mixture a solution of 48 parts (0.8 mole) of glacial acetic acid and 10.8 parts (0.6 mole) of water was added with stirring over a 4-minute period. This mixture was refluxed for about 7 hours. A solution of 46.75 parts (0.1 mole) of a C_{14+} olefin sulfonic acid (Saponification No.=130), 20 parts pale oil and 180 parts naphtha was added to the mixture; and the mixture was refluxed for 30 minutes. Sulfur dioxide was then passed into the mixture for 58 minutes at about 0.830 part/minute. The SO_2 rate was reduced to about 0.1 part/minute and the methanol, water, and acetic acid were distilled off. The mixture was cooled to 85° C. and about 5 grams of water were added. The mixture was then refluxed until 8.9 grams of a liquid was collected in the water collector. The collecting of liquid, the water addition and refluxing were repeated two more times, collecting 7.1 parts of liquid the first time and 6.2 parts of liquid the second time. The total time during which the sulfur dioxide was introduced at the reduced rate during this sequence was about 5.5 hours. At the end of this time, the SO_2 flow was discontinued and nitrogen was passed through the mixture. The temperature was then raised to 145° C. to remove the remaining water. On cooling, the mixture was diluted with about 200 parts of benzene. The mixture was filtered with a bed of Celite Filter-aid. The solvents were removed under vacuum. The product obtained was a clear, dark fluid. The yield was 128.8 parts. Analysis of the product showed 30.6% Ba and 7.96% S. The infrared spectrum showed some acetate presence.

EXAMPLE 12

The process of Example 11 was repeated using 79.6 parts (0.4 mole) of black ash, instead of 0.3 mole of black ash and 30 parts of pale oil instead of 20 parts of pale oil.

The product obtained was a clear, dark moderately viscous material. The yield was 160.2 parts. Analysis

11

showed it to contain 33.2% Ba and 8.31% S. The infrared spectrum showed some acetate present.

EXAMPLE 13

A vessel fitted as in Example 1 was charged with 56.4 parts (0.3 mole) of black ash (89.6% assay) and 100 parts of methanol. To this mixture a solution of 48 parts (0.6 mole) of glacial acetic acid and about 10.8 parts (0.6 mole) of water was added over a 5-minute period. This mixture was refluxed for about 7.25 hours. To this mixture, a solution of 61.1 parts (0.1 mole) of a C₁₄+ olefin sulfonic acid (Saponification No.=92), 20 parts pale oil (Sun Circosol 410), and 180 parts naphtha (aviation alkylate) was added and the mixture was refluxed for 30 minutes. SO₂ was then passed into the mixture at a rate of about 0.830 part/minute for 58 minutes. The SO₂ rate was reduced to about 0.1-0.14 part/minute and methanol, water and acetic acid were distilled off. The mixture was cooled to 85° C. and about 5 parts of water were added. The mixture was then refluxed until 11 parts of liquid were collected in the water collector. This sequence of cooling, adding about 5 grams of water followed by refluxing and then collecting a liquid was repeated two more times; 8.2 parts of liquid were collected the first time and 6.2 parts were collected the second time. The total time during which the sulfur dioxide was introduced into the mixture at a reduced rate during this sequence was 5.33 hours. At the end of this time sulfur dioxide treatment was discontinued and nitrogen was passed into the mixture; the mixture was then heated to 143° C. to remove the remaining water. The mixture was cooled and then diluted with about 200 parts of benzene. This mixture was filtered through a bed of Celite Filter-aid. The solvents were then removed under vacuum. The product thus obtained was a clear fluid; the yield was 146 parts. Analysis showed it to contain 27.8% Ba and 7.37% S. The infrared spectrum showed the presence of some acetate.

EXAMPLE 14

A vessel fitted as in Example 1 was charged with 75.6 parts (0.4 mole) of black ash (89.6% assay) followed by about 100 parts of water. To this mixture 60 parts (1.0 mole) of glacial acetic acid was gradually added with stirring over a 7-minute period. The reaction mixture was then heated at reflux for 8 hours. At the end of this time a solution of 46.75 parts (0.1 mole) of a C₁₄+ olefin sulfonic acid (Saponification No.=130), 30 parts pale oil and about 40 parts naphtha. This mixture was heated at reflux for 30 minutes, cooled to 60° C. and about 4 grams of methanol were added. Sulfur dioxide was passed into the mixture at a rate of about 0.830 part/minute for 52 minutes at a reaction temperature ranging from 58° C.-72.5° C. The sulfur dioxide flow was then reduced to 0.1 part/minute and water, acetic acid and methanol were distilled off. The treatment time with sulfur dioxide at the reduced rate was about 4 hours. The sulfur dioxide flow was discontinued when the temperature of the mixture reached 139° C. The temperature was then raised to 150° C. to remove the remaining water. After cooling the mixture, it was diluted with about 200 grams of benzene. This product mixture was then filtered through a bed of Celite Filter-aid. The solvents were removed under vacuum. The overbased barium product obtained was a cloudy fluid. The yield was 143.9 parts. Analysis showed it to contain 31% Ba and 8.11% S. The infrared spectrum showed some acetate present.

The olefin sulfonic acid used in Examples 11-14 was obtained by SO₃ sulfonating the C₁₄+ olefin composition G of Table 2.

Similar overbased products are obtained when ethanol or pentanol is used in place of methanol in the above examples. Sulfonic acids prepared from olefins disclosed herein also produce overbased barium products analogous to those of the examples above. Similar results are also

12

obtained if toluene, n-butylbenzene, catalytic reformate mixtures, aviation alkylates, light refining oils, or other suitable petroleum refinery streams are used in place of the pale oil/naphtha medium in the examples above. Similar products are also obtained when the examples above are carried out at 150° C. and under pressure where necessary.

The overbased barium olefin sulfonate products of the present invention are useful as additives to distillate hydrocarbon fuels. These distillate fuels include residual fuel oils, home heating fuels, kerosene, and the like. In distillate fuels, these overbased barium additives may act as sludge dispersants, corrosion inhibitors or combustion improvers. An especially important use for these overbased barium olefin sulfonates is as smoke suppressing additives in distillate fuels; and particularly in fuels used for internal combustion engines. These overbased sulfonates are especially effective in diesel fuels. Suitable diesel fuels are Federal Specification VV-F-800, Grades DF-A, DF-1, DF-2, and DF-4 was well as Classes 1, 2, 3, and 4 diesel fuels. Marine diesel fuel oils are also improved by the overbased sulfonates of the present invention. A tabulation of useful distillate fuel oils is presented in "Fuels and Lubricants," Milosh Popovich and Carl Hering, pages 134; 146-153, John Wiley and Sons, Inc., New York (1959).

The useful concentrations for these overbased barium sulfonates in distillate fuels will vary. Concentration ranging from about 0.05% to about 3% by weight, for example, are useful for suppressing smoke.

These distillate fuel compositions constitute another embodiment of the present invention. Following the example of the such distillate fuel compositions; all percentages are by weight unless otherwise noted.

EXAMPLE 15

A distillate fuel composition is prepared by adding 0.5% of the product of Example 5 to a No. 2 burner fuel oil (Federal Specification VV-F-815).

EXAMPLE 16

A distillate fuel composition is prepared by adding 2.5% of the product of Example 7 to a No. 6 burner fuel oil (Federal Specification VV-F-815).

EXAMPLE 17

A distillate fuel composition is prepared by adding 1.0% of the product of Example 6 to a No. 5 burner fuel oil (Federal Specification VV-F-815).

EXAMPLE 18

A distillate fuel composition is prepared by adding 0.2% of the product of Example 4 to kerosene.

EXAMPLE 19

A distillate fuel composition is prepared by adding 1.5% of the product of Example 1 to a No. 1 burner fuel oil (Federal Specification VV-F-815).

EXAMPLE 20

A distillate fuel composition is prepared by adding 0.05% of the product of Example 8 to a No. 4 burner fuel oil (Federal Specification VV-F-815).

EXAMPLE 21

A diesel fuel composition is prepared by adding 0.05% of the product of Example 2 to a Class 1 diesel fuel.

EXAMPLE 22

A diesel fuel composition is prepared by adding 3% of the product of Example 4 to a Class 2 diesel fuel.

EXAMPLE 23

A diesel fuel composition is prepared by adding 0.07% of the product of Example 1 to a Class 3 diesel fuel.

13

EXAMPLE 24

A diesel fuel composition is prepared by adding 0.1% of the product of Example 3 to a Class 4 diesel fuel.

EXAMPLE 25

A diesel fuel composition is prepared by adding 2.5% of the product of Example 5 to a Grade DF-A diesel fuel.

EXAMPLE 26

A diesel fuel composition is prepared by adding 0.15% of the product of Example 7 to a marine diesel fuel.

EXAMPLE 27

A diesel fuel composition is prepared by adding 0.25% of the product of Example 8 to a Class 3 diesel fuel.

EXAMPLE 28

A diesel fuel composition is prepared by adding 0.2% of the product of Example 1 to a Class 4 diesel fuel.

EXAMPLE 29

A diesel fuel composition is prepared by adding 0.3% of the product of Example 8 to a Class 1 diesel fuel.

EXAMPLE 30

A diesel fuel composition is prepared by adding 0.4% of the product of Example 9 to a Class 2 diesel fuel.

EXAMPLE 31

A diesel fuel composition is prepared by adding 0.5% of the product of Example 11 to a 30 cetane number diesel fuel.

EXAMPLE 32

A diesel fuel composition is prepared by adding 1.0% of the product of Example 13 to a Class 3 diesel fuel.

EXAMPLE 33

A diesel fuel composition is prepared by adding 1.5% of the product of Example 14 to a marine diesel fuel.

EXAMPLE 34

A diesel fuel composition is prepared by adding 0.7% of the product of Example 12 to a Grade DF-4 diesel fuel.

The distillate fuel compositions of the present invention may contain other additives such as cetane improvers, cold flow improvers, antioxidants, dyes and the like.

The overbased barium sulfonates of the present invention reduce the smoking tendency of distillate fuels. For example, noticeably less smoke is emitted from a diesel engine when it is operating on the fuel composition of Example 27 than when operating on Class 3 diesel fuel which does not contain the overbased barium sulfonates of the present invention. Similarly, less smoke is produced when using the burner fuel composition of Example 7 than when using No. 5 burner fuel which does not contain the overbased product of the present invention.

The smoke reducing effect of the overbased barium olefin sulfonates of the present invention was determined in a diesel engine test using the Hartridge smoke meter for the smoke measurements. The procedure involved running the engine under a certain set of conditions, first with the base diesel fuel containing no smoke reducing additive. The smoke number for this base fuel was set at 100% relative smoke. The smoke numbers of the base fuel containing a barium additive of the present invention as well as the base fuel containing a commercial smoke reducer were then determined under the same conditions. The smoke numbers of the fuels containing the additives were then compared to the base diesel fuel smoke number. The relationship of these smoke numbers was then expressed in terms of percent relative smoke.

14

Data obtained for such a series of tests is tabulated below. The base diesel fuel used was a commercial No. 2 distillate.

TABLE 5.—EFFECT OF ADDITIVES ON DIESEL FUEL SMOKE

Test	Additive	Concen- tration, g./Ba/gal.	Relative smoke, percent
1	None	—	100
2	Additive L ^a	2.05	35.7
3	Product of Example 4	1.93	34

^a A commercial barium containing smoke reducing diesel fuel additive.

The data clearly show that the overbased product of the present invention (Example 4) is a very effective smoke reducer in diesel fuel; and is slightly better than a commercial barium-containing diesel smoke reducer. This data is representative of the smoke reducing effectiveness of the overbased barium products of the present invention.

Commercial diesel fuels containing about 0.4% by weight of the product of Example 8 or the product of Example 12 were also shown to have acceptable resistance to water emulsification, as measured by an accepted commercial resistance-to-emulsification test.

The present invention encompasses three embodiments:

- (1) a procedure for preparing overbased barium olefin sulfonates,
- (2) the overbased barium olefin sulfonate product, and
- (3) the use of these overbased products in distillate fuels.

All three embodiments have been fully described in the foregoing disclosure and it is desired to limit this invention only within the spirit and scope of the following claims.

I claim:

1. A process for preparing an overbased barium sulfonate which comprises:
  - (1) preparing a mixture of barium sulfide in from about 100 to about 800 parts by weight of C₁-C₅ alkanol per mole of barium sulfide, adding at least an equimolar amount of water based on barium sulfide and at least 2 moles of acetic acid per mole of barium sulfide,
  - (2) heating said mixture to reflux and maintaining said temperature until the evolution of H₂S has substantially stopped,
  - (3) adding thereto a mixture of an inert hydrocarbon medium and an olefin sulfonic acid, prepared by sulfonating a mixture of acyclic, monoolefins having from about 12 to about 32 carbon atoms, such that the molar ratio of barium sulfide to said sulfonic acid is from about 1:1 to about 10:1,
  - (4) introducing sulfur dioxide gas into the heated mixture of Step (3) until the sulfur dioxide effluent rate is substantially equal to the sulfur dioxide input rate, and
  - (5) distilling substantially all the alkanol, acetic acid and water from said mixture.
2. The process of claim 1 wherein said barium sulfide is a crude barium sulfide.
3. The process of claim 2 wherein said molar ratio of barium sulfide: olefin sulfonic acid is from 2:1 to 5:1, and said alkanol is methanol.
4. The process of claim 3 wherein said mixture of olefins comprises even carbon numbered olefins containing less than about 3% by weight of C₁₂ and lower olefins wherein at least 50% of the olefins are alpha olefins.
5. The process of claim 4 wherein said molar ratio of barium sulfide:sulfonic acid is 3:1 to 4:1.
6. The process of claim 3 wherein said mixture of olefins comprises by weight 0-6% C₁₈ and lower olefins, a trace—22% C₁₈ olefins, 32-55% C₂₀ olefins, 18-39% C₂₂ olefins, 6-16% C₂₄ olefins, 0.5% C₂₆ olefins, and 0-10%

15

C_{28} and higher olefins, wherein the distribution of olefin configuration in said mixture is 10-32% internal, 30-55% vinyl, and 30-55% vinylidene.

7. The process of claim 6 wherein said molar ratio of barium sulfide:sulfonic acid is 3:1 to 4:1.

8. The product prepared by the process of claim 1.

9. The product prepared by the process of claim 2.

10. The product prepared by the process of claim 4.

11. The product prepared by the process of claim 6.

12. The product prepared by the process of claim 7.

13. A distillate fuel oil containing from 0.5-3% by weight of the product prepared by the process of claim 1.

14. A diesel fuel containing a smoke reducing quantity of the product prepared by the process of claim 1.

15. A diesel fuel containing a smoke reducing quantity of the product prepared by the process of claim 2.

16. A diesel fuel containing a smoke reducing quantity of the product prepared by the process of claim 3.

17. A diesel fuel containing a smoke reducing quantity of the product prepared by the process of claim 4.

16

18. A diesel fuel containing a smoke reducing quantity of the product prepared by the process of claim 5.

19. A diesel fuel containing a smoke reducing quantity of the product prepared by the process of claim 6.

5 20. A diesel fuel containing a smoke reducing quantity of the product prepared by the process of claim 7.
